CONCRETE ROAD JOINT

Clifford Older, Wilmette, Ill.

Application November 16, 1936, Serial No. 110,960

8 Claims. (Cl. 94—18)

The present invention relates to concrete road joints, and many of the features of the invention may be embodied in both the type of joints called expansion joints and contraction joints.

5 The present application is a continuation in part of my prior application, Serial No. 80,281, filed May 18, 1936 for Concrete expansion and contraction joint.

One of the objects of the present invention is 10 the provision of an improved concrete road joint construction, including improved means for assuring the alignment of the adjacent sections of concrete, such means permitting the relative sliding movement between these sections.

15 In any joint in which steel is used for dowel purposes, either in the form of a continuous steel plate or separate dowel bars or rods, the stiffness of the steel member is usually much greater than that of the concrete. Both are elastic, but the 20 relative stiffness of steel to concrete is about fifteen to one; that is, within the elastic limits of the materials, concrete yields about fifteen times as much as steel under the same unit pressure. Therefore, in a doweled joint, the deflection is 25 much more dependent upon the yield of the concrete than upon that of the steel. If the deflection is to be held to a minimum, the unit pressure on the concrete must be reduced to the smallest feasible amount.

30 The stiffness of the dowel plates or bars depends upon their bending resistance, but the dowel may be made as stiff as desired, simply by making its vertical dimension in proportion to the bending resistance desired. However, the thickness of the concrete roadway is generally pre- 35 determined by other considerations than that of the resistance of the joint, and is usually set forth in the specifications relating to the construction.

One of the objects of the invention is the provision 40 of an improved concrete roadway joint in which the deflection from the normal or no load plane or position of the roadway to the position under load is reduced to a minimum.

Another object of the invention is the provision 45 of an improved concrete road joint, in which vertical play is eliminated, and in which the doweling structure is as stiff as possible with respect to the vertical deflection of the concrete sections at the joint.

50 Another object of the invention is the provision of an improved doweling structure for concrete road joints which is of maximum stiffness without resorting, in the preferred embodiment, to expensive machining of the parts, and which 55 results in the distribution of the pressures on

the concrete over such large areas as to not only eliminate pressures in excess of the elastic limit of the concrete, but to reduce them to such an extent that the elastic yield will be a minimum.

Another object of the invention is the provision 5 of an improved doweling structure for concrete road joints in which the tendency of the dowel member to split or spread the parts of the concrete section in which the dowel member slides is resisted by an improved structure which 10 practically eliminates any possibility of deflection due to this action.

Another object of the invention is the provision 15 of an improved concrete road joint unit, the parts of which may be shipped "knocked down" and which may be made of stock parts that can be assembled on the job.

Another object of the invention is the provision 20 of an improved concrete road structure, the parts of which may be constructed of sheet metal so that the parts of the joint may be constructed by stamping operations, thereby reducing the cost of the finished joint.

Another object of the invention is the provision 25 of an improved concrete expansion or contraction joint, the parts of which are adapted to nest with each other so that they may be more conveniently shipped.

Other objects and advantages of the invention 30 will be apparent from the following description and the accompanying drawings, in which similar characters of reference indicate similar parts throughout the several views.

Referring to the three sheets of drawings accompanying the specification,

Fig. 9 is an elevational view of the doweling unit of Fig. 8, looking from the right end of the figure, with the concrete omitted.

Referring to Fig. 1, 10 indicates in its entirety the concrete roadway joint unit, which is shown in connection with the adjacent edges of two concrete sections 11 and 12. The improved doweling structure may comprise a stock metal member 13 of substantially T shape having the top of the T located as the vertical flange 14 and the stem of the T as the dowel plate or horizontal flange 15. The vertical flange 14 is preferably provided with a multiplicity of anchoring lugs 16, 17, which are formed by being punched out of the body of the flange 14 at the top and at the bottom, and bent in opposite directions so that the lugs 16, 17 are staggered with respect to each other and extend at right angles to the flange 14. These lugs are preferably tapered in width so that they are widest at their outermost edges and are thereby anchored in the concrete sections 11 and 12.

The concrete section 11 may be provided with the usual reinforcement, but certain portions of the reinforcing are preferably arranged in connection with the dowel structure as shown in Fig. 1. The horizontal rods 18, 19 may be located above the lugs 16 and below the lugs 17, and these rods may be secured to vertical rods 20, sufficient in number and equally spaced, as shown in Fig. 3, to connect the doweling structure with the reinforcing.

In some embodiments of the invention the anchoring lugs 16 and 17 may be welded to the rods 18, 19 or 20, the rods 20 being placed adjacent lugs 16 or 17.

The dowel plate flange 15 comprises a metal member of uniform thickness which is slidably mounted in the concrete section 12. This may be accomplished by means of a sheet metal shield 21, which has two parallel legs 22, 23, joined by a U shaped bend 24. The width of the parallel portions 22, 23 of the shield 21 is greater than the portion of the plate 15 which is located between these flanges, leaving an air space 25 just inside the U shaped bend 24 to permit initial expansion of the concrete. The flanges 22 and 23 tightly engage the dowel plate 15 by virtue of their own resiliency and by virtue of the fact that they are bent to such shape that they spring towards the plate 15, when the plate 15 is removed from between the flanges 22 and 23.

The shield 21 is provided with the upwardly and downwardly extending flanges 26, 27 respectively, which may be of sufficient length in a contraction joint to serve as a division plate for assuring the formation of a crack at the joint unit 10.

They may also be used in a contraction joint for clamping between the vertical flange 14 and the flanges 26, 27 suitable sheet metal division plates. In the expansion joint structure as shown in Fig. 1, they have the additional function of providing a support for holding the core units 28, 29. The flanges 26, 27 are also preferably provided with the inwardly turned edges 30, 31 which engage in the concrete of the sections 11 and 12 and provide additional anchorage for the shield unit 21.

One of the most important functions of the flanges 30, 31 is the distribution of the load which is placed upon the flanges 22 and 23, over a greater area of concrete. The loads which are placed upon the concrete sections 11 and 12

at the joint tend among other things to cause a split of the concrete section 12 between the flanges 22, 23. This deflection is resisted by the concrete as well as the shield 21, and the flanges 22, 23 distribute the forces exerted upon the concrete at the shield over a greater area. These forces are transmitted to the flanges 30 and 31 by the vertical flanges 26 and 27, and thus the force is transmitted to parts of the concrete not immediately adjacent the flanges 22 and 23, which also assist in resisting forces tending to cause deflection.

The concrete section 12 is also preferably provided with the usual reinforcing, a portion of which is located as shown in Fig. 1, with vertically extending rods 32 located at regularly spaced points and welded to the horizontal rods 33, 34.

The vertical rods 32 are as close as possible to the joint contacting the U-shaped bend 24, to which they may be spot welded, if desired.

When the doweling structure is embodied in an expansion joint, it is provided with the core members 28 and 29. These core members may be identical in construction and may consist of relatively thin sheet metal, such as steel, which is adapted to bend when the concrete expands into the spaces 35, 36, after the concrete has hardened, but the core members 28, 29 are of material sufficiently stiff to support the expandable members 37, 38, and to act as end forms for sections of concrete, keeping the concrete out of the spaces 35 and 36.

Each core unit may comprise a pair of vertical flanges 39, 40, which are substantially parallel and which are joined by the bottom flange 41 (referring to core 28). The bottom flange 41 is bowed inward with respect to the core unit 28 so as to facilitate its crushing or folding, after its function of forming the joint has been performed, and when the expansion takes place.

The parallel walls 39, 40 of the core unit 28 may be provided with laterally extending flanges 42, 43 located below the expandable member 37 so as to provide a wider space 44 at that point to assure the fact that the expandable member 37 will never be pinched between the adjacent sections 11, 12 of the concrete.

Laterally extending flanges 42, 43 support the upwardly extending parallel flanges 45, 46, which may terminate short of the upper surface of the concrete sections 11 and 12 and are adapted to support the flexible seal 37.

The present joint may be used with various types of flexible sealing members, and the flexible sealing member 37 is merely exemplary of one of the preferred types. It comprises a flexible metal member made of non-corrodible material, such as sheet copper, having a central flexible portion 47, which may comprise the lower flat flange 48 and two upwardly extending flanges 49, 50. The upwardly extending flanges 49, 50 each terminate in a partially cylindrical bead 51, 52, the other edges of which are attached to the downwardly extending flanges 53, 54 respectively.

Each downwardly extending flange may carry a laterally projecting flange 55, which is provided with an upwardly turned edge 56, serving as an anchoring formation.

The member 57 may comprise a preformed filler of initially plastic composition, which fills the groove in the upper part of the flexible seal 37, and which may also serve in leveling off the concrete.

The flanges 49 and 53 slidably engage the flanges 45, and the flanges 50, 54 slidably engage the flange 46 so that the seal is suitably supported on the core member 28. The core member 28 fits between the flanges 14 and 26, resting on the dowel plate 15. The structure of the lower core 29 and flexible sealing member 58 at the bottom may be similar to that previously described.

The beads 51, 52 in each of these sealing members may be filled with a compressible or crushable cord 59, which serves to hold the sealing member on the flanges of the core in predetermined position with the bend of the bead spaced from the upper edge of the flanges 45, 46.

The operation of this crushable filler is as follows: When the joint is installed, the parts are held in the position of Fig. 1, the upper flexible seal resting on the flanges 46, 56, the edges of which engage the crushable filler 59. At a later date, when the concrete is hard and the concrete contracts, the widening of the space 35 and extension of the flexible seal 37 causes the beads 51, 52 to be pulled downward. The use of the crushable filler 59 provides such a space above the edges of the core plates 45, 46 that these edges will not cut the beads 51, 52 from the inside.

Referring to Fig. 2, this is a modification in which all of the parts described may be identical except that the shield member 21 is provided with a different form of member for transmitting force and distributing it with respect to the concrete section 12. In this case the horizontally extending edge 30 has been omitted, but the vertical flange 26 of the shield 21 has also been provided with laterally projecting anchoring lugs 60, similar in form to the lugs 16, 17 on the dowel member 13. These lugs perform the same function as the flanges 30, as force exerted on the flanges 22, 23 is transmitted by the flanges 26 and 27 to the anchoring lugs 60, which are anchored in the concrete. These anchoring lugs are arranged with respect to the reinforcing bars or rods 18, 19, 20, as previously described.

Referring to Fig. 3, this is a fragmentary view of the doweling structure as seen from the right of Fig. 2, with the other parts of the joint unit omitted. It will be seen that the shield 21 is provided with regularly spaced and preferably staggered anchoring lugs 60 located midway between the reinforcing rods 20. Anchoring lugs 60 engage inside the rods 18 and 19, which are welded to the rods 20, and thus the end of the concrete section 12 is further reinforced against splitting by the interengagement of the anchoring lugs 60 with the reinforcing members.

Referring to Fig. 4, this is another modification, showing one form of expansion joint which may be constructed according to the present invention. The dowel plate 61 comprises a flat steel plate of suitable thickness, which may be slidably mounted at one or both sides in a suitable shield assembly 62 or 63. The shield member 62 is substantially identical in construction to shield 21, previously described, and it works in the same way, except that in this case the shield member 62 may be made of very thin metal, not sufficiently capable, by its own action, of clamping the dowel plate 61 as tightly as desired.

This shield member 62 is, however, engaged by a clamping member 64, which has the substantially U-shaped upper portion provided with flanges 65, 66 that clamp the flanges of the shield 62 against the plate 61.

The clamping member 64 may have a standard 75 67 which is provided with a foot 68 to provide it

with a stable supporting surface. The foot 68 has an aperture 69 for receiving a stake 70, which is so driven that it passes through the aperture 69 into the sub-grade and engages the clamping member 64 adjacent the upper end of the stake. 5

The joint may be provided with the core members previously described, or with any suitable filler strips 71, 72, such as a crushable material, one example being "Celotex." Any suitable flexible copper seal 73 may be used at the top and/or 10 the bottom. For example, the flexible seal 73 comprises a U-shaped flexible portion 74, the downwardly extending flanges of which terminate in anchoring flanges 75, preferably having anchoring formations 76. 15

The groove above the flexible seal 73 is filled with an initially plastic composition 77. The vertical flanges of the shield members 62 and 63 engage the filler members 71, 72 and hold the unit in assembled relation. 20

A shield or socket for a dowel plate that is in one piece, as shown at the left side of Fig. 4, presents difficulties in manufacture as regards the tight flat fit of the dowel plate and socket. It is desirable for economy to use commercially 25 rolled plates for the socket or shield and for the dowel plate.

Such commercially rolled plates of the same nominal thickness vary somewhat in actual thickness because of the "tolerance" in thickness 30 required by the rolling mills. Hence the slot of a single piece shield must be made wide enough in the vertical direction to accommodate the thickest dowel plate 61 permitted by the mill tolerance. The thickness of the plates would 35 vary within this tolerance, and the thinnest dowel plate 61 of the same nominal thickness would then have a vertical play in the socket 62 or 63.

This small vertical play may not in all cases be 40 seriously detrimental, and whenever it is desired to use single piece sockets, such as the shield 62, either the socket slot, the dowel plate 61, or both, may be machined, if deemed necessary. This, however, involves considerable expense, and the 45 structure shown at the right of Fig. 4 is adapted to accomplish a sliding fit more economically, regardless of the mill tolerance in plate thickness.

In this embodiment of the invention the shield 63 is made in three sections 78, 79, 80. Each of 50 the sections 78 and 80 may be similar in shape, being provided with horizontal flange 81, vertical flange 82, and horizontal flange 83. The section 79 may consist of a substantially U-shaped cap or cover of relatively thin metal, which fits over 55 the horizontal plates of sections 78 and 80 and provides the usual space 25 for lateral movement of the dowel plate 61.

A plurality of spring clamps 84, located at points along the sections 78—80, where clamping is needed, or where they may do the most good, clamp the horizontal flanges 81 into engagement with the dowel plates 61 and effect a tight, flat contact between these members. For this purpose the clamping members 84 may be 65 of substantially U shape, with inwardly curved engaging portions 85 having aligned contact with the flanges 81.

In this embodiment the sections are again 70 preferably suitably reinforced as described with respect to Figs 1 and 2.

Referring to Fig. 5, this is a modification which again may be utilized in either expansion or contraction joints, but is shown in connection with an expansion joint of the type of Fig. 4. The 75

dowel plate 86 may be similar in form to those previously described, except that it is provided with a plurality of spaced apertures 87 on one side for rivets 88, and slots 89 on the other side 5 for slidably receiving the bolts 90. The dowel plate 86 is secured on one side of the joint to a pair of sections 78 and 80, similar to those described in Fig. 4, the horizontal flanges 81 being secured to the dowel plate by the through rivets 10 88.

Referring again to Figs. 8 and 9, in another embodiment of the invention, which requires only one type of unit, both of the sides of the doweling structure may be provided with a unit 15 identical to the socket unit 102, and a rod 104 may be provided which is shorter than the composite length of the bore 25 in both units. Then it would be necessary to manufacture only one type of unit 102 and provide it with a sliding rod, 20 and both sides of the joint would look like the right half of Fig. 8.

The plate 86 and assembled parts are supported in suitable position by the clamping member 64, similar to that described in respect to 25 Fig. 4, except that the short horizontal flange 83 of the section 80 is slotted to receive the standard 67 of the clamping member.

The right hand supporting unit in Fig. 5 comprises a pair of sections 91, 92, similar in form 30 to the sections 78, 80, described in Fig. 4, except that they are provided with wider horizontal flanges 93, which may have the inwardly curved edges 94 for receiving the thin sheet metal cap 95, similar to the cap 79, previously described. 35 The horizontal flanges 93 of sections 91, 92 of the shield member may be secured in tight engagement with the dowel plate 86 by the screw bolts 90, which pass through apertures in the flanges 93 and through a slot or oval aperture 89 in the dowel plate 86.

The initial position of the bolt 90 with respect 40 to the ends of the slot 89 may be that the bolt is centrally located in the slot so that motion is permitted in either direction. Suitable lubrication 45 may be used between the flanges 93 and the dowel plate 86, such as mica lubricant. The operation in this embodiment is the same as those previously described, except that the tendency toward the spreading of the slot in the shield or 50 socket for the dowel plate is resisted by the bolt 90, which is suitably located to most effectively resist such deflection.

The apertures 89, which have been described 55 as slots, may be more economically made as round holes, since then they may be drilled. As shown in Fig. 5 in section, the aperture may be either a slot or a circular bore.

Although the bolt 90 tightly clamps the flanges 60 93 to the dowel plate 86, sliding motion is permitted without damage to any of these members, the right hand shield being anchored in its concrete section by means of the projecting bolt portions, and the left hand shield being anchored by means of the projecting rivet portions. 65

In this embodiment of the invention, the cap 95 need not be made of metal, but may consist of a strip of adhesive tape, such as zinc oxide tape or gummed waterproof paper, thereby further reducing the cost in this respect. 70

Referring to Fig. 6, this is another modification, the right hand portion of which is similar to that of Fig. 5, except that a rivet 96 may be used instead of the bolt 90. In this case the 75 dowel plate 97 is similar in construction to the

dowel member 13 of Fig. 1, except that the plate is provided with slots 98. The slots 98 are located to receive each of the rivets 96 and a cylindrical spacing member or washer 99. The washer 99 permits the flanges 93 to be riveted together on 5 each side of the washer without engaging the dowel plate 97 too tightly.

The slots 98 and rivets 96 are located at regularly spaced points along the doweling unit, and substantially all play is eliminated from the 10 doweling unit by the structure shown. The other details of this joint may be as described with respect to the prior embodiments, and the same numerals have been applied to indicate corresponding parts. 15

Referring to Fig. 7, this is another embodiment of the invention in which the left hand side of the joint may be as shown in Figs. 4, 5, or 6, but that selected to illustrate the invention is similar to Fig. 5. The dowel plate is again provided with the elongated slots 98 in one edge of the plate, at regularly spaced intervals, and shield sections 91, 92, similar to those described in Fig. 5, are employed in connection with a strip of adhesive tape 95 for closing the crack between 20 them. 25

In this embodiment the horizontal load transmitting flanges 93 have been made wide enough to permit the application of a bolt 100, which passes through the dowel plate 101 through the 30 flanges 93 and through the flanges 83. The slot 98 is merely wide enough to permit sliding movement of the bolt 100, and the bolt 100 clamps the sectional parts 91, 92 of the right hand shield member slidably on the dowel plate 101, and substantially eliminates all play. 35

The bolt is also in position to effectively resist any spreading of the flanges 93, due to the action of the dowel plate, and in this embodiment the forces caused by deflection are not only distributed throughout the end of the concrete section, but the tendency toward deflection is resisted by the bolt 100. 40

Referring to Figs. 8 and 9, this is a doweling structure which may be constructed of cast metal. 45 The right hand part of the unit comprises a circular dowel socket member 102, which is provided with a cylindrical bore 103 of greater length than the dowel 104, thereby providing the usual expansion space 25.

The dowel member 105 may consist of a substantially cylindrical body provided with the cylindrical dowel rod 104 projecting therefrom. Each of these members, that is, the dowel socket member 102 and the dowel member 105, may be provided with a face disc 106 and an outer circular bearing flange 107. The face disc performs the function of the flange 26 of Fig. 1, transmitting part of the stress to the flange 107, which is suitably anchored in the concrete and 60 adapted to transmit forces exerted on it to the adjacent part of the concrete section. 65

The cylindrical bodies of the socket member 102 and dowel member 105 are preferably provided with radially extending bearing flanges 108 (Fig. 9), and a threaded member 109 may be located in one wall of the socket member 102 to engage the dowel rod 104. Threaded member 109 secures the socket member 102 on the dowel rod 104, but does not prevent movement due to expansion 70 after the concrete has hardened. 75

In other embodiments of the invention the thumb screw 109 may be eliminated and the parts held in position by frictional engagement of the bore 103 with the dowel rod 104. In this case the 75

5 circular flange 107 and wing flanges 108 permit the socket to be rotated to any position without affecting its bearing on the concrete, and a tight fit may be secured by machining both the dowel and the socket.

10 It will thus be observed that I have invented an improved doweling structure for concrete road joints which may be utilized in either expansion joints or contraction joints. As distinguished 15 from the devices of the prior art in which there is a tendency for the concrete below or above the dowel plate to split off before the dowel plate is stressed to full capacity, the present invention is adapted to eliminate the possibility of this destruction of the concrete and to distribute the 20 load throughout the concrete.

25 The doweling arrangements described herein are of maximum stiffness, reducing deflection to a minimum and practically eliminating any lost motion or play.

30 The structure of the present devices is such that the forces exerted on the dowel plate tending to spread the dowel plate socket are more effectively resisted, and such spreading is prevented. The 35 present devices may be constructed at a low cost on account of the sheet metal construction, and they may be shipped in knocked down condition and assembled on the job.

30 In the preferred embodiment of the invention machining of the parts is practically eliminated, thereby further reducing the cost, and the play resulting from the difference in thickness of dowel 35 plates permitted by mill tolerance is also eliminated.

35 While I have illustrated a preferred embodiment of my invention, many modifications may be made without departing from the spirit of the invention, and I do not wish to be limited to the precise details of construction set forth, but 40 desired to avail myself of all changes within the scope of the appended claims.

45 Having thus described my invention, what I claim as new and desire to secure by Letters Patent of the United States, is:

50 1. In a doweling structure for concrete road joints, the combination of a metal dowel plate with a pair of adjacent concrete sections, said metal dowel plate having one edge carried by the 55 first concrete section and having the opposite edge slidably mounted in the other concrete section, the dowel plate in said other concrete section being engaged on both sides thereof by separate sheet metal members, a cap strip cooperating with said separate sheet metal members for forming a slot in said other section of concrete, and clamping means engaging said separate members at a plurality of spaced points for holding 60 said separate members in tight engagement with said dowel plate during the construction of the joint, said clamping members comprising a plurality of substantially U-shaped metal clamps engaging on the opposite faces of said separate members.

65 2. In a doweling structure for concrete road joints, the combination of a dowel plate of substantially uniform thickness, said dowel plate having one edge provided with anchoring means adapted to be anchored in a concrete section of the roadway, and the other edge being adapted to 70 be slidably mounted in the adjacent section of the roadway, a shield for said other edge, comprising a pair of sheet metal members provided with flanges of greater width than the amount of said dowel plate initially projecting into said other section, each of said flanges being pro-

vided with an inwardly turned edge whereby the edges of said flanges approach each other, and means for closing the crack between said edges, comprising a cap strip, said dowel plate having a slot, and a securing member passing through apertures in said shield and binding the parts of said shield into tight engagement with said dowel plate to resist the splitting tendency of the dowel plate on the concrete. 5

3. In a doweling structure for concrete road joints, the combination of a dowel plate of substantially uniform thickness, said dowel plate having one edge provided with anchoring means adapted to be anchored in a concrete section of the roadway, the other edge being adapted to be 10 slidably mounted in the adjacent section of the roadway, a shield for said other edge, comprising a pair of sheet metal members provided with flanges of greater width than the amount of said dowel plate initially projecting into said other 15 section, each of said flanges being provided with an inwardly turned edge whereby the edges of said flanges approach each other, means for closing the crack between said edges, comprising a cap strip, said dowel plate having a slot, and a 20 securing member passing through apertures in said shield and binding the parts of said shield into tight engagement with said dowel plate to resist the splitting tendency of the dowel plate 25 on the concrete, said securing member comprising a rivet provided with spacing means in said slot, said spacing means predetermined the spacing of the parts of said shield. 30

4. A dowel plate for concrete road joints comprising a member of substantially T-shaped cross 35 section, the top of the T being arranged in vertical position transversely to the direction of the roadway, and the stem of the T serving as a dowel plate, said vertical portion of said member being provided with a multiplicity of anchoring 40 lugs punched out of said member and adapted to be embedded in a concrete section. 45

5. In a concrete road joint, the combination of a pair of concrete roadway sections separated by a crack, with a metal load transmission member having a plane sliding surface extending in the general direction of expansion or contraction movement of the ends of said sections, and carried by the first of said sections, said load transmission member extending across the crack between said sections and slidably engaging the second of said sections, and a metal shield member having a plane surface adapted and located for sliding contact with the plane surface on said load transmission member, said shield member being backed up by concrete of said second section, and means for securing the plane surfaces of said members in tight contact with each other during the setting of the concrete, whereby a tight sliding engagement between said plane 55 surfaces and immediate load transmission from one section to the other without substantial play is assured, said means comprising a metal member extending through said load transmission member and said shield member, to bind said 60 members together, said load transmission member being slotted to permit sliding movement of said metal member in said slot. 65

6. In an expansion joint for concrete roadways, the combination of a dowel plate member which is 70 adapted to extend into two adjacent sections of concrete at the edges thereof, said dowel plate member having parallel sides, with a metal shield constructed of sheet metal, and having a pair of parallel flanges joined together at a yoke 75

extending across one edge of said dowel plate, said parallel flanges extending to a point between the sections of concrete, each parallel flange supporting a vertically extending flange, one of said vertically extending flanges extending upwardly 5 and the other extending downwardly, with a filler supported by said joint against said vertically extending flanges, said filler being adapted to be compressed when the concrete expands, and means extending through said dowel plate and 10 through said parallel flanges for drawing said parallel flanges into close contact with said dowel plate, said dowel plate member being provided with a slot for receiving said means extending through said dowel plate, and said slot extending 15 in the direction of its expansion and contraction of the joint whereby sliding movement of the shield and dowel plate member is permitted, the said latter means moving with said shield.

7. In a concrete road joint, the combination of 20 a pair of concrete sections with a dowel plate, said dowel plate having one edge anchored in one concrete edge, and having the other edge slidably mounted in a slot in the adjacent concrete section, said slot being provided with a metal lining 25 above and below said dowel plate, and a metal member extending through said metal lining and said dowel plate, said dowel plate having a slot therein for said metal member, and said latter

slot extending in the direction of movement of the parts of said joint, said metal member binding said metal lining to said dowel plate, to secure a close sliding fit and immediate load transmission and permitting the sliding movement of the parts of said joint as the concrete shrinks or expands. 5

8. In a concrete road joint, the combination of a pair of concrete sections with a dowel plate, said dowel plate having one edge anchored in one concrete edge, and having the other edge slidably mounted in a slot in the adjacent concrete section, said slot being provided with a metal lining above and below said dowel plate, and a metal member extending through said metal lining and said dowel plate, said dowel plate having a slot therein for said metal member, and said latter slot extending in the direction of movement of the parts of said joint, said metal member binding said metal lining to said dowel plate, to secure a close sliding fit and immediate load transmission and permitting the sliding movement of the parts of said joint as the concrete shrinks or expands, said metal member being provided with a spacer in the slot of said dowel plate, and said spacer preventing the excessive binding of said shield against said dowel plate at said metal member. 10 15 20 25

CLIFFORD OLDER.
